(57) **CLAIM**

The ornamental design for a toddler bike with trailer, as shown.

DESCRIPTION

FIG. 1 is a perspective view of a toddler bike with trailer showing my new design;

FIG. 2 is a front view thereof;

FIG. 3 is a right side view thereof, the left side being a mirror image;

FIG. 4 is a top view thereof;

FIG. 5 is a back view thereof; and,

FIG. 6 is a bottom view thereof.

The portions of the article shown in broken lines in the drawings are for illustrative purposes only and form no part of the claimed design.
